(57) **CLAIM**

The ornamental design for a mobile workstation, as shown and described.

DESCRIPTION

FIG. 1 is a top, front and left side perspective view of my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof, the right side elevational view being a mirror image;

FIG. 7 is a top, rear and left side perspective view thereof;

FIG. 8 is a top, front and left side perspective view of an alternate embodiment of my new design;

FIG. 9 is a top plan view thereof;

FIG. 10 is a bottom plan view thereof;

FIG. 11 is a front elevational view thereof;

FIG. 12 is a rear elevational view thereof;

FIG. 13 is a left side elevational view thereof, the right side elevational view being a mirror image; and,

FIG. 14 is a top, rear and left side perspective view thereof. The broken lines of FIG. 3 and FIG. 10 depicting connector plates are for illustrative purposes only and form no part of the claimed design.
